UNITED STATES PATENT OFFICE.

WILLIAM D. HAMILTON, OF BEARSDEN, SCOTLAND.

WATER-TUBE BOILER.

SPECIFICATION forming part of Letters Patent No. 660,506, dated October 23, 1900.

Application filed February 16, 1900. Serial No. 5,494. (No model.)

To all whom it may concern:

Be it known that I, WILLIAM DAVID HAMILTON, a citizen of the United Kingdom of Great Britain and Ireland, residing at Campsie View, Bearsden, Scotland, have invented certain new and useful Improvements in and Relating to Water-Tube Boilers, of which the following is a specification.

This invention has reference to improvements in and relating to water-tube boilers, the object of the invention being to cheapen and simplify the manufacture of such boilers by dispensing with the usual cross-boxes connecting the tube-headers with the steam and water drum and with the necessity for sinuous-shaped headers for staggering the water-tubes to direct the fire-gases in a sinuous course among these.

The appended drawings, together with the following specification, fully describe the nature and object of my invention.

Figure 1 of the drawings is a sectional view, taken lengthwise, of a boiler constructed with the above-mentioned object. Fig. 2 is a sectional view similar at right angles to Fig. 1. Fig. 3 is a sectional view similar to Fig. 2, but showing a slightly-different method of directing the fire-gases in a sinuous course among the water-tubes. Fig. 4 is a sectional view, to a larger scale, taken across the steam and water drum, showing the method of connecting the headers with the dished portions of the steam and water drum in a boiler having nine sections of tubes in the width of the boiler. Figs. 5 and 6 are similar views to Fig. 4, but showing only eight and six sections of tubes, respectively, in the width of the boiler. Fig. 7 is a sectional view of the hand-hole fittings. Fig. 8 is a view, to a larger scale, showing the method of joining and butt-strapping the drum at the dished portion of the same.

In that part of my invention relating to the connection of the headers with the steam and water drum A instead of, as is ordinarily practiced, dishing the under shell of the drum A at each end thereof outward and downward or making a separate cross-box of corresponding shape and riveting the same over an opening in the under side of the drum I dish said under portion inward entirely within the drum by a simple crease. The sides B of the

creased portion extend vertically or approximately vertically from the outer circumference of the drum A inward within said drum, 55 cutting it for a certain distance inward transversely in two planes, the inner ends of these sides B having a horizontal portion B' extending between them, as shown by the various figures of the drawings. The horizontal portion B' of the crease forms a chord to that arc of the drum from which the crease starts and is subtended by this arc, which joins its extremities, and into this portion B' nipples C are expanded, as also into headers D, of rectangular cross-section, into which the water-tubes E, situated in the combustion-chamber E' of the boiler, are expanded. Thus in a boiler having six sections of tubes in its width, as shown at Fig. 6, the four central 65 nipples C extend in straight lines from the dished portion of the drum A to the headers D, and the outer nipples at either side are expanded through the curved drum-shell, at right angles thereto, being first bent in order 70 that they may enter their headers D at the proper angles. By the method of connecting the nipples C to the creased horizontal portion B' and the curved portion of the drum-shell A the outer bent nipples are rendered 75 more accessible than the outer nipples in any outwardly-dished cross-box, and in order to admit of the dishing of the steam and water drum shell A being done in a thorough practical manner those portions of the shell at the 80 front and rear which are to be dished are each made of two plates, butt-strapped at their meeting ends, as shown particularly at Fig. 8. Referring to that portion of my invention relating to the shape of the headers 85 D, I make these of rectangular cross-section and straight throughout their length instead of sinuous, as heretofore practiced, thus dispensing with the necessity for using collapsible mandrels and avoiding the expense and 90 waste of time in manipulation entailed by such mandrels, and in order to direct the fire-gases among the water-tubes E in a sinuous course I place at intervals in the manner shown at Figs. 2 and 3 over these water-tubes E fire-bricks F, extending lengthwise 95 of the water-tubes, which act as baffles and have the effect of rows of tubes connected in sinuous-shaped headers. Between each row 100

of tubes E hinged cleaning-doors G are fitted in the side walls at an angle to open inwardly and arranged to close automatically when the steam cleaning-pipe is withdrawn. Hand-holes H are also formed in the outer faces of the front and rear headers D opposite each tube for easy access to the latter and are fitted with clamp and cap forgings I J, the head of the clamp I being inside the header D overlapping the hand-hole H and the stem passing outward through the hand-hole to the outer side of the cap J, where it is secured by a cap-nut K. The header D is recessed on its outer side around the hand-hole H to receive a ring L, of copper or other soft metal, and the bearing-face of the cap J has a valve-ring face J' formed on it, which bears upon the copper or other ring L when the cap J is screwed up, thereby forming a water-tight joint.

Having now described the invention, what I desire to secure by Letters Patent is—

In a boiler, the combination, with a steam-drum provided with a crease on its under side which projects wholly within the drum, of 25 headers arranged under the drum, straight nipples secured in holes in the inner headers and in the bottom plate of the said crease, and nipples having curved portions at their upper ends and secured in holes in the outer headers and in the curved part of the shell of the drum at the ends of the said crease, substantially as set forth.

In witness whereof I have hereunto set my hand in presence of two witnesses.

WM. D. HAMILTON.

Witnesses:

CHARLES BYARS,
DAVID CAMPBELL.
